WARREN E. DANLEY, OF HIGHLAND PARK, ILLINOIS, ASSIGNOR TO FANSTEEL PRODUCTS COMPANY, INC., OF NORTH CHICAGO, ILLINOIS, A CORPORATION OF NEW YORK.

HIGH-FREQUENCY FILAMENT-HEATING MEANS.

Application filed October 6, 1927. Serial No. 224,328.

My invention relates to high frequency filament heating means and pertains more particularly to the use of said means with a radio receiver, this application being a continuation in part of my co-pending application, Serial No. 191,800, filed May 16, 1927. Heretofore attempts to use inaudible frequency for heating the filaments of radio receiving sets have been unsatisfactory due to the instability of the set, to the tendency of the grids to swing positive and draw excessive current, to the fact that signal frequency builds up regeneration in the succeeding stages, to the fact that the oscillator tube 10 may be damaged by excessive currents caused by improper manipulation of the set, to the fact that the high frequency current of the filament circuit tends to heterodyne with an undesired signal, and to the fact that any 20 ripple in the power source modulates the filament heating current to cause that ripple to become audible in the loud speaker. The object of this invention is to overcome these difficulties.

25 A further object is to provide a radio receiver with a power source in which the filaments of the thermionic tubes are directly heated by a current of more than double the highest frequency of the signals to be received.

30 A further object is to eliminate all undesirable modulations of filament supply current by providing means for balancing irregularities in the plate power supply of the high frequency generator (the oscillator tube) by introducing corresponding irregularities of proper amplitude and phase in the grid circuit of said oscillator tube.

35 A further object of the invention is to provide a negative bias on the grid of the oscillator tube sufficient to prevent excessive plate current therein under any and all operating conditions.

40 A further object is to provide means to insure that the grids of the tubes whose filaments are heated by this device will not swing positive and draw current. Negative bias on the grid has heretofore been used (1) to restrict the plate current of the tube to a desired value, (2) to operate the tube on a desired part of its characteristic curve, and (3) to provide against the grid of the

tube drawing current due to a positive swing as a consequence of the signal voltage. My invention, however, provides for the use of 55 additional negative bias to compensate for the excessive grid swing due to the superimposing of the filament supply voltage on the signal voltage.

A further object is to provide a signal 60 frequency filtering system in the filament circuit to increase the stability of the set.

A further object is to provide an automatic regulator whereby the filament power supply means will accommodate itself to 65 variations in input voltage and output load.

A further object is to provide an improved radio receiving set combined with its power supply.

Other objects will be apparent as a detailed description of the invention proceeds.

A preferred embodiment of my invention is illustrated in the accompanying drawings, in which like parts are represented by similar reference characters throughout the several views.

Fig. 1 represents the schematic diagram of my improved radio receiver and power supply means.

Fig. 2 is a diagram showing the same 80 power supply means, the drawing being simplified and parts omitted in order to show more clearly the oscillation generator.

Fig. 3 illustrates diagrammatically a means for eliminating any ripple in the 85 plate current supply of the oscillation generator.

Fig. 4 is a detail showing the coupling of the inductances in the oscillation generator.

Fig. 5 is a modification showing the use 90 of a signal frequency filtering system in the filament circuit of the radio receiver.

Figs. 6 and 7 are diagrammatic details of the filament circuit explaining the action of the above filter system.

95 The circuit illustrated in Fig. 1 includes an antenna 10, a six-stage receiver 11, a "B" current supply 12, and an "A" current supply 13. The ground wire or zero potential conductor 14 connects the set to ground at 100 15. A conductor 16 connects conductor 14 to the negative side 27' of the "B" current supply. The antenna circuit is inductively connected to a conventional radio receiver illus-

trated as stages I, II, III, IV, V and VI. This receiver provides three stages of radio frequency amplification, a detector and two stages of audio frequency amplification. The radio frequency stages may be neutralized in any well-known manner, a conventional neutrodyne system being shown in the drawing.

Power to operate this receiver is furnished from the ordinary alternating current power mains through wires 17 to the primary winding 18 of a transformer. This transformer is provided with three secondary windings 19, 20 and 21. The terminals 15 of secondary 19 are connected by conductors 22 to the filament of an oscillation generator 42. The terminals of secondary 20 are connected by conductors 23 to the plates of thermionic rectifier tubes 24. The filaments of these tubes are heated by current from secondary 21 supplied through conductors 25, as shown in the drawing. A conductor 26 connects the center of secondary 21 to choke-coil 28, the other terminal 25 of which is connected to conductor 26' which is the positive side of the "B" current supply, and a conductor 27 taps the center of secondary 20 and leads to conductor 27' which is the negative side of the "B" current supply and which is connected to ground as above stated. On each side of the choke-coil 28 are bridged filter condensers 29 and 30, which co-act with choke-coil 28 to smooth out the pulsations in the rectified current.

Bridged across conductors 26' and 27' is a resistance 31. This resistance is tapped by a conductor 32 which leads to the plate circuit feed wire 33. The tap is made at 40 a point which will give the desired plate voltage, which will necessarily depend on the receiving set used. A resistance 34, which serves to further reduce the voltage on the plate of the detector tube, is inserted 45 between conductor 32 and conductor 35, which latter conducts the plate current for the detector tube. A condenser 36 is connected between conductors 35 and 27' and a condenser 37 is connected between conductors 35 and 26', their function being to cooperate with resistance 34 to more perfectly filter or smooth out the detector plate supply voltage.

A negative bias resistance 38 is connected 55 between the negative "B" current supply 27' and a conductor 39 leading to the center of the secondary 19. This resistance effects a negative bias on oscillator tube 42 and power amplifier tube VI. Its use in connection with tube 42 is shown in Figs. 1 and 3. The plate current flows from positive "B" (26') to the plate of the tube, through the tube to the filament and from the filament through 22, 39, and resistance 38 to negative "B" (27'). The IR drop

across this resistance 38 obviously maintains the filament positive with respect to negative "B", and since the grid is connected to negative "B" through 27' and 52, the filament is maintained positive with respect to 70 the grid, or, in other words, the grid is negatively biased with respect to the filament.

To operate efficiently, an oscillator tube requires a very high negative bias. It would be wasteful to secure all this bias by means 75 of an IR drop across resistance 38. Accordingly grid condenser 43 and grid leak 44 are provided to give the major part of the required bias. But the condenser grid leak combination is effective to provide bias only 80 when the tube is oscillating whereas resistance 38 provides a bias under all conditions of operation. The combination of these two methods is therefore an important feature, being economical of power on the one 85 hand, and on the other hand, providing against damage to the oscillator tube from the excessive plate current which would follow any cessation of oscillations if the grid leak condenser method were used alone. 90

A condenser 40 is connected between conductors 27' and 39 in shunt with resistance 38 and a condenser 41 is connected between conductors 26' and 39. The function of these condensers is clearly shown in Fig. 3. Since 95 conductor 39 taps the center of secondary 19 which heats the filament of oscillator 42, it will at all times be at the mean potential of said filament. The grid of oscillator tube 42 is connected to 27', the negative side of 100 the "B" current supply, through the grid condenser 43 in parallel with grid leak 44 and through 27' and 52. The plate of the oscillator tube is connected through 26'' and 45 to the positive side of the "B" current 105 supply 26'.

While the voltage across 26' and 27' is substantially constant, there may be superimposed upon it a slight ripple due to the AC power source. Thus while the average 110 value is V_1 , the maximum value will be V_2 and the minimum value V_3 . When the voltage is increased as at V_2 , the plate current is likewise increased, and when the plate voltage decreases the plate current is decreased, thus causing a ripple in the current taken by the oscillator which necessarily modulates the high frequency oscillating current. 115

If, however, the negative bias on the grid 120 is increased by an amount equal to:

increase in plate voltage,
amplification constant of tube,

the increase in negative grid bias will tend 125 to decrease the plate current by the same amount that the increase in plate voltage tends to increase the plate current. In the same way a decrease in plate voltage is balanced by a corresponding decrease in 130

negative bias. Fig. 3 diagrammatically illustrates one method of accomplishing this result.

Power for heating the thermionic valve filaments of the radio receiver is supplied by oscillation generator 13 which includes a three electrode tube 42 of which the plate is connected through conductor 26" and inductance 45 to the positive "B" current supply 26'. The grid is connected through grid condenser 43 in shunt with grid leak 44, conductor 27" and inductance 52 to the negative side of the "B" current supply 27', as above stated. The inductance 45 is inductively coupled with inductance 52 as shown by Fig. 4, i. e., both inductances are wound on the same tube, and in the same direction. A condenser 46 is connected between conductor 26" and the feeder 47 of the filament supply circuit. Leading from feeder 47 are conductors 48 to the respective filaments and each filament circuit also includes a condenser 49 and a conductor 50 leading from the condenser to conductor 14. A condenser 51 is connected between the conductor 14 and the positive side of the "B" current supply 26', it being connected at the opposite end of inductance 45 from the connection of condenser 46 as shown in the drawing. Condenser 46 serves primarily to tune the oscillating circuit. Condensers 49 and 51 serve primarily as blocking condensers; they form low impedance paths for high frequency current but block direct current.

A resistance 53 is connected between feed wire 47 and conductor 14, its function being to provide negative bias for the grids of the tubes in stages I, II, III, and V. Each grid is connected to conductor 14 by conductor 50, as shown in the drawing, and since there is always a voltage drop across resistance 53, due to the flow of plate current through it, the filament in each tube (connected by conductor 48) will be maintained at a higher potential than the grid, or, in other words, the grid will have the necessary negative bias. This is most important in my circuit because additional negative bias is required, due to the additive effect of the filament power voltage, and the signal voltage, tending to cause the grid to swing positive and draw current. Failure to supply this large negative bias for the grid may result in the failure of the set using high frequency current for filament power.

In order to prevent plate circuit interstage coupling in the radio frequency stages, I have inserted in each stage a filter consisting of resistance 54 and condenser 56. Resistance 54 is connected between the plate feed wire 33 and the conductor 55 and condenser 56 between conductor 55 and the filament of the tube. Resistance 54 forms a high impedance for signal frequencies and condenser 56 forms a low impedance for

said frequencies so that the signal tends to return through 56 to the filament circuit without traveling through 33, 32, 27', 16, 14 and 50, which might otherwise prove a troublesome common impedance. In the fourth stage (the detector circuit) I provide condenser 64 and condenser 65, as shown in the drawings. These condensers serve to bypass radio frequency and audio frequency, respectively, from the plate circuit of the detector tube to the filament thereof.

The six-stage radio receiver shown is a conventional type and further description of it is not deemed necessary. The tube in the sixth stage operates the loud speaker 80 and its filament is heated by current from secondary 19 through conductors 22'. The plate of this tube is connected by conductor 57 to a choke-coil 58, the other end of which is connected by conductor 59 to the positive side of "B" current supply 26'. Conductor 57 is also connected to condenser 60, the other side of which is connected by conductor 61 to loud speaker 62, which is connected by conductor 63 to the center of secondary 99 19.

The filaments of the tubes in the receiving set are heated by an oscillating current set up in the circuit 45, 46, 47, 48, 49, 50, 14 and 51. Sufficient energy is supplied by tube 42 95 to compensate for the energy lost in heating the filaments. The circuit is tuned by condenser 46 which is very small as compared to condenser 51. The voltage drop across inductance 45 is equal to the voltage drop 100 across condenser 46 added to that of the filament circuit and to that across condenser 51 and condensers in parallel therewith. Thus if the voltage drop across 45 were 400 volts, across 46 were 394 volts, and across 51 were 105 1 volt, the voltage drop across the filament circuit would be 5 volts.

Feed-back from one stage to a preceding stage may occur in the grid filament circuits and to avoid this, I may use separate filament heating circuits as shown in Fig. 5. To better understand the reason for this expedient, reference is made to Figs. 6 and 7 in which I have schematically illustrated grid filament circuits of the first three stages 115 of my receiver, as shown in Fig. 1. Assuming an amplification per stage of 10 and a signal voltage of unity on grid g_1 , the voltage on grid g_2 would be 10 and on g_3 would be 100. In each tube there is a small grid 120 to filament capacity represented diagrammatically with respect to the two sides of the filaments by c_1 , c_1' , c_2 , c_2' , c_3 and c_3' . Any currents from grids to filaments through the capacities c_1 , c_2 and c_3 find a path to ground 125 of practically negligible resistance through conductors 50 and so are the source of no ill interstage effects. The case is different with the current flowing through capacities c_1' , c_2' and c_3' . The resistance of each fila- 130

ment is about 20 ohms and that of the connecting wires is negligible. Therefore, the current flowing from P_3 may flow through filament f_3 to ground, but the resistance of this filament makes some of this current take the path 48_3 , 47, 48_2 to P_2 and 48_3 , 47, 48_1 to P_1 , the voltages at points P_3 , P_2 and P_1 being approximately equal. At P_2 and P_1 the current again divides, part flowing through filaments f_2 and f_1 and part through the paths c_2' , g_2 and c_1' , g_1 , respectively. Thus, instead of unity voltage at g_1 , there will be a greater voltage due to the high order of the voltage at g_3 , this constituting regenerative feed-back.

In the case of a receiver whose filaments are heated by radio frequency, the common methods of preventing or diminishing this feed-back (by-pass condensers across filaments, etc.) cannot be used. In Fig. 7 I have schematically shown a method of cutting down this feed-back adapted for radio frequency filament heating means. I have, in effect, eliminated the common filament feed wire 47 and have substituted a plurality of tuning condensers $46_1'$, $46_2'$, $46_3'$ for the single tuning condenser 46 of Figs. 1 and 6. Each of these condensers $46_1'$, $46_2'$, $46_3'$ will offer a very high impedance to the passage of current of signal frequency. In other words, instead of the direct path from P_3 through 48_3 , 47 and 48_1 to P_1 , this current will have to travel through 48_3 , 46_3 , $26''$, $46_1'$ and $48_1'$ to P_1 , as shown in Fig. 7, impressing but slight voltage at P_1 .

The filtering effect of the arrangement shown in Fig. 7 is of a higher order than ordinarily required. Usually a separation of the tubes into two groups, as shown in Fig. 5, is all that is necessary. It should be noted that when separate filament heating circuits are used, separate resistances 53' must also be used, as shown in Figs. 5 and 7, the function of which is the same as above described with reference to Fig. 1.

From the above description, it will be a simple matter for anyone skilled in the art to construct a radio receiver and power supply therefor in accordance with my invention. For the six-stage set, three stages of radio frequency, a detector and two stages of audio frequency, I have found that the following values will give good results.

Tubes in stages 1 to 5 are of the type known as 201A tubes, i. e., they are the standard receiving tubes whose filaments require .25 amps. at 5 volts, whose detector plate voltage is usually 22.5 to 45 and which operate satisfactorily as amplifiers with a plate voltage of 135 and a negative grid bias of 9 volts.

Tube 42 and the tube in stage VI are of the type known as 210 tubes; they use 7-7½ volts A. C. for heating filaments and their plates require about 400 volts D. C.

Tubes 24 are of the type known as 216B and they require 7 to 7½ volts A. C. and 550 volts (R. M. S.), respectively, on filaments and plates

115 volts A. C. across conductors	17	70
7.5 volts across the terminals of secondary	19	
1100 volts across the terminals of 20		
7.5 volts across the terminals of 21		
100 henries for coil 28 (at 100 m. a. of pure D. C.)	75

400 ohms for resistance 53		
800 ohms each for resistance 53' of Fig. 5	100	
5000 ohms for resistance 54		

Inductance 45 and capacity 46 (in series with 49 and 51, which have negligible tuning effect), are so chosen as to satisfy the two following formulas, the first having to do with the frequency of oscillation and the second with obtaining maximum output from the oscillator tube.

$$(1) f = \frac{159200}{\sqrt{L} \text{ microhenry} C \text{ microfarad}}$$

$$(2) C = \frac{I_{op}L}{E_{op}R_L} \text{ or } L = \frac{E_{op}R_L C}{I_{op}}$$

where f is frequency in cycles
 C is capacity in farads
 L is inductance in henries
 I_{op} is plate current in amperes
 E_{op} is plate voltage in volts
 R_L is resistance in ohms

The oscillating circuit constants may be so chosen that the maximum output of the oscillator tube, with given values of oscillator plate voltage, oscillator filament voltage, and oscillator grid bias, will be just sufficient to heat a given maximum number of filaments. The filaments to be heated are connected in parallel. Therefore, if the number of filaments is diminished the resistance

R_L is increased and, from (2), if the oscillating circuit constants are unchanged, the power output of the oscillator tube will fall off. In other words, to an important extent, the power output will be automatically adjusted to the diminished load. Similarly, when L and C are proportioned to give maximum tube output for a certain minimum plate voltage, E_{op} , the efficiency of the oscillator will fall off with any increase in the plate voltage. For, from (2) again, maximum tube output is obtained only with a certain ratio of plate voltage E_{op} to plate current I_{op} and this ratio will vary as E_{op} is increased for, in a vacuum tube oscillator, plate current is proportioned not to plate voltage but to the sum: plate voltage plus amplification constant times grid voltage. Therefore, to an important extent the power output may be made independent of fluctuations in the power supply voltage. Thus the automatic regulation referred to above is obtained.

A feature of my invention is the use of a frequency which prevents undesirable heterodyne effects. I have found that the use of a filament current frequency, less than double the greatest signal frequency for which the receiver is designed, will give said undesired heterodynes. For example, a filament current frequency of 30,000 cycles may heterodyne with a signal frequency of 1,030,000 cycles to produce a beat of 1,000,000 cycles which would interfere with reception of a signal frequency of 1,000,000 cycles. At the other extreme, a filament current frequency of 1,990,000 cycles may heterodyne with a signal frequency of 990,000 to produce a beat of 1,000,000 cycles. But if a filament current frequency of over 2,000,000 cycles is used with a receiver which will not handle a signal of over 1,000,000 cycles, no beat is possible. I have also found that, due to the importance of stray capacity and resistance effects encountered in the use of high frequencies, it is desirable to avoid the use of any higher frequency than that necessary to meet the above requirement.

While I have described a preferred embodiment of my invention, it is understood that I am not limited to the details set forth. Any receiving circuit may be used in place of the neutrodyne set illustrated. Instead of the balancing condensers for eliminating the effect of ripple in the plate current supply of the oscillator tube, I may employ other means for accomplishing this result. For example, when the ripple in the plate voltage is of the same frequency as the current for heating the filament of the oscillator, the grid return of the oscillator tube may be connected to the movable arm of a potentiometer whose terminals are connected to the two filament leads, and so adjusted as to give a balancing effect. Any rectifier may

be used in place of the thermionic rectifier shown. A direct current source of proper voltage may be used instead of alternating current with necessary changes in "B" supply circuits, etc.

I have also found that approximately the same adjustment of the circuit constants as outlined above yields most satisfactory operation from the standpoint of elimination of audible disturbances traceable to fluctuations in the power source, for example, the hum tending to be present due to the commercial current power input.

It will be noted also that the term "connected" appears in certain of the claims. Attention is directed to the fact that where the filament heating current is of high frequency, as in the present case, this term does not necessarily imply a conductive or galvanic connection, but includes also inductive or capacitive connection, since the high frequency current can readily pass through either a condenser or a transformer coupling in a circuit.

I do not limit myself to the wiring scheme, to values given in my preferred embodiment, nor to any other details except as defined by the following claims:

1. In combination, a radio receiver including filament and plate circuits, an oscillation generator for generating currents of ultra audio frequency differing from the received signal frequency, connections for supplying power to said plate circuit and to said generator, and connections for supplying oscillating filament heating current from said generator to said filament circuit.

2. In combination, a radio receiver having plate and filament circuits, an ultra audio frequency oscillation generator for generating currents of ultra audio frequency differing from the received signal frequency, connections for supplying power to said plate circuits and said generator, connections for supplying oscillating filament heating current from said generator to said filament circuits, and means for preventing modulation of the ultra audio frequency output of the oscillation generator.

3. In combination, a radio receiver including a filament circuit, an ultra audio frequency oscillation generator comprising a thermionic valve having cathode, anode and control electrodes, connections between the electrodes and a power source and to said filament circuit, and means for inducing on the grid of said tube a change in the negative bias equivalent in effect to any change in anode voltage, whereby modulation of the said ultra audio frequency oscillations produced by the generator is prevented, and an unmodulated heating current is produced in said filament circuit.

4. In a combined power supply and radio receiver including thermionic valves and

- their circuits, means for heating the filaments of the thermionic valves of the radio receiver by high frequency oscillating current, and means for supplying to the grid 5 of each valve a negative bias sufficient in magnitude to compensate for its tendency to swing positive with respect to its filament due to the additive effect of the filament and signal voltages.
- 10 5. In combination, a multiple stage radio receiver, including thermionic valves, and ultra audio frequency current, generator circuit for supplying heating current to the filaments of said thermionic valves, and 15 means comprising series capacities in said circuit for isolating the separate stages of the receiver whereby regeneration of a signal and consequent oscillation are prevented.
6. In combination, an oscillation generator 20 including a three electrode tube, a power source for said oscillation generator, means for eliminating ripple from power supplied to said generator, a thermionic valve filament circuit electrically connected to said generator whereby the oscillating current heats the filaments, and means for maintaining a negative bias on the oscillation generator tube whether the tube is oscillating or not.
- 30 7. In combination, a radio receiver including plate and filament circuits, an oscillation generator, means for supplying power to said generator and to said plate circuit, and means for supplying power from said 35 generator to said filament circuit, said oscillation generator producing a current of a frequency more than double that of any signal frequency for which the receiver is designed.
- 40 8. Means for stabilizing a multiple stage radio receiver using high frequency "A" current supply which includes an impedance between the filament of one tube and the filament of another tube, said impedance serving to prevent signal frequency feed back 45 between grid filament circuits and also to tune an oscillating circuit in said "A" current supply.
9. In combination, a transformer provided with a plurality of secondary windings, an oscillation generator, a rectifier, a filter circuit, connections from one secondary to the generator, other connections from said transformer through said rectifier and 55 said filter to said generator, a plurality of thermionic valves having filaments, grids and plates, connections from said generator to said filaments, connections from said rectifier through said filter to said plates, 60 and a resistance in the plate circuit return from the filaments to said rectifier connected to provide negative bias on the grids.
10. In a power supply unit, a transformer, a rectifier, a filter circuit, connections between them terminating in positive and 65
- negative direct current conductors, a resistance bridged across said conductors, an oscillation generator comprising a three electrode thermionic tube, connections from said direct current conductors to said oscillation generator, connections from the terminals of a transformer secondary to the tube filament, a resistance between the center of said secondary and said negative direct current conductor, and impedance units 70 bridged between said center and said positive and negative direct current conductors, respectively, whereby modulations of the plate current of the oscillator tube are prevented.
11. In combination, a multiple stage radio receiver including plate, grid and filament circuits, an oscillation generator including a three electrode thermionic tube, positive and negative connections for supplying "B" 85 current to said plate circuits, an inductance in the plate circuit of the oscillator tube, condensers bridged from each side of said inductance to each side of the receiver filament circuit, said condensers, inductance 90 and receiver filament circuit forming the oscillating circuit of said oscillation generator, and connections from the grid circuits to the filament circuits comprising resistances and condensers bridged across said resistances. 95
12. In combination a radio receiver including plate and filament circuits, an oscillation generator, an oscillation circuit fed by said generator and connected with said filament circuit, said oscillation circuit being 100 tuned to a frequency of more than double that of any signal frequency for which the receiver is designed.
13. In combination a radio receiver including plate and filament circuits, an oscillation generator, an oscillation circuit fed by said generator and connected to said filament circuit, said oscillation circuit being tuned to a frequency immediately above the frequency double that of any signal for 105 which the receiver is designed whereby heterodyne effects are avoided and power losses are maintained at a minimum.
14. In combination a radio receiver including a plurality of separated filament 115 circuits, an oscillation generator, an oscillation circuit fed by said generator, said oscillation circuit being connected through impedance to said separated filament circuits respectively whereby the path of signal frequency current in the filament line is impeded.
15. In combination, an oscillation generator, a radio receiver including a filament circuit, connections for supplying energy to 125 said generator including an inductance unit, capacity units connected from the terminals of said inductance unit to the opposite sides of the filament circuit, said capacity and inductance units being elements in an oscil- 130

lation circuit for supplying filament current at proper amperage and voltage to the tubes of the radio receiver.

16. The method of operating a thermionic valve having a cathode and a control electrode which comprises heating the cathode thereof by ultra audio frequency oscillating current and maintaining the control electrode thereof sufficiently negative with respect to the cathode to prevent any substantial flow of current through the control electrode.

17. In a combined power supply and radio receiver, including thermionic valves and their circuits, means for producing ultra audio frequency heating currents in cathode circuits of said valves, said heating currents being of a frequency differing from the signal frequency, said means including a thermionic generator tube, having an impedance in its grid circuit to maintain a negative bias while the tube is oscillating by virtue of the grid current, and a separate means for maintaining an independent negative bias on the grid whether the tube is oscillating or not.

18. In combination a multiple stage radio receiver including thermionic valves, an ultra audio frequency current source for heating the cathodes of said valves, a plurality of cathode heating circuits, and means comprising series capacities to substantially isolate said circuits from one another with respect to signal frequency, whereby regeneration at signal frequency and consequent oscillation are prevented.

19. In combination a radio receiver including a plurality of thermionic valves and their circuits, and a source of ultra audio

frequency current connected with the cathode circuits of said valves, said source comprising an oscillation generator and an oscillation circuit, the constants of said oscillation circuit being so adjusted with respect to the load that the impedance in the work circuit of the oscillation generator is substantially resisted only and substantially equal to the internal resistance of said generator whereby approximately maximum power output is obtained.

20. In combination, a radio receiver including a plurality of thermionic valves and their circuits, and a source of ultra audio frequency current connected with the cathode circuits of said valves, said source comprising an oscillation generator and an oscillation circuit, the constants of said oscillation circuit being so adjusted that any audible disturbances due to fluctuations in the power supplied to the source are minimized in the output of the radio receiver.

21. In combination, a radio receiver including a plurality of thermionic valves and their circuits, and a source of ultra audio frequency current connected with the cathode circuits of said valves, said source comprising an oscillation generator and an oscillation circuit, the constants of said oscillation circuit being so chosen with respect to the load that the current supplied to the said cathode circuits is approximately proportioned to the load and for a given load is maintained substantially independent of variations of voltage supplied to the source.

In witness whereof, I hereunto subscribe my name this 30th day of September, 1927.

WARREN E. DANLEY.
